TABLE

Frank R. Torrey, 9805 Dallas Ave.,
Silver Spring, Md. 20901

Filed Feb. 19, 1971, Ser. No. 117,192

Term of patent 14 years

Int. Cl. D6—03

U.S. Cl. D6—177

FIG. 1

FIG. 3

FIG. 1 is a perspective view of a table, showing my new design;

FIG. 2 is a side elevational view, the other side being a mirror image thereof, and

FIG. 3 is an end elevational view, the other end being a mirror image thereof.

I claim:

The ornamental design for a table, as shown and described.
